UNITED STATES PATENT OFFICE

2,630,305

TOWER PACKING

Raymond C. Scofield, La Marque, and Josef Krahé, Texas City, Tex., assignors to Pan American Refining Corporation, Texas City, Tex., a corporation of Delaware.

Application April 29, 1949, Serial No. 90,286

12 Claims. (Cl. 261—94)

1

This invention relates to a tower packing employing a plurality of undulating foraminous contacting mats which are superposed to form a plurality of transverse cells, and more particularly the invention is an improvement on that described and claimed in a copending Scofield application S. N. 713,833, filed November 30, 1946, which is now Patent Number 2,470,652 dated May 17, 1949.

A primary object of this invention is to provide a method and means for contacting vapors and liquids which is particularly adapted for large diameter commercial construction and wherein substantially the entire cross-sectional area of the column is effective as a region for such contacting. Another object of the invention is to provide a prefabricated packing of simple and inexpensive construction, and which is substantially self-supporting for considerable heights. A further object of this invention is to provide a method and means for supporting superposed undulating mats in aligned relation without obstructing the flow of vapors and liquids through the packing. An additional object of this invention is to provide positive means for maintaining the superposed undulating mats in capillary contact so as to define a multiplicity of cells. A further object of the invention is to provide a self-supporting packing which can be employed in the modification of existing towers. These and other objects of the invention will become apparent to those skilled in the art as the description of the invention proceeds.

The objects of this invention are attained by disposing a plurality of quadrilateral skeleton cages within the cells defined by the superposed undulating mats. These quadrilateral skeleton cages prevent the deformation of the lower mats by the weight of the upper mats and also position adjacent mats so that the troughs of the upper mat are aligned with the ridges of the lower mat. To assure positive contact along the ridges and troughs when the aligning quadrilateral skeleton cages are in place, tie rods are provided which pass through the multiplicity of mats and compress the packing and force the mats in close engagement with each other along the troughs and ridges and with the quadrilateral skeleton cages therebetween. By this combination of quadrilateral skeleton cages and tie rods, it is possible to use mats of variable shape and to fabricate them with greater tolerances than was possible heretofore.

As disclosed in the copending application, the system broadly comprises a column including su-

2

perimposed foraminous packing units defining a plurality of generally symmetrical cells bounded by multi-layers of non-filming meshed structures to provide a repeatedly divided path for the liquid 5 downwardly and laterally and a tortuous but continuous path upwardly for the gasiform material. The flow behavior and contact efficiency of the packing of the type to which this invention relates is, however, influenced by several characteristics of the packing. Thus, the number of foraminous sheets comprising the individual mats, the slope of the ridges and troughs, and the amplitude of the undulating mats are correlated to attain the optimum operation. For fractionation operations normally carried out at atmospheric pressure an overall height of about four inches is appropriate, the sides forming an angle with the horizontal in the range of from 10 40 to 50 degrees. For relatively higher liquid loadings such as are encountered in elevated pressure operation somewhat better performance may be obtained by increasing the angle with the horizontal to a value in the range of from 15 40 to 75 degrees. For relatively lower liquid loadings such as are encountered in vacuum operation the performance is improved by reducing the angle with the horizontal to a value in the range of from 25 to 50 degrees. These amplitudes and slopes change when the packing mats 20 are deformed and if the mats are not aligned properly the cells may be by-passed and the flow of liquid may be erratic. Accordingly, the quadrilateral cages are of such shape as to define the 25 cells between the adjacent undulating mats and maintain the walls of the cells at an angle of 30 between 25 and 75 degrees with the horizontal, i. e. at these angles, with the plane of contact 35 between the adjacent mats.

A packing unit or mat may comprise multiple 40 layers of self-supporting non-filming meshed structures shaped to provide inclined surfaces on the upper and lower boundaries of the mat. More particularly, these units may comprise a plurality of inter-locking or integral elements 45 comprising filaments or strands of metal, plastics, plastic impregnated fabric mesh and the like. We prefer, however, to employ sheets of foraminous materials such as hardware cloth, wire screening, expanded metal lath and the like. The size of 50 the foramina is important and should be such that liquid having a surface tension within 25-70 dynes per centimeter at working temperatures will not be supported in a continuous film. In general, interstices of between 0.15 and 0.5 inch 55 are preferred for large scale installations but

other meshed structures having larger or smaller openings can be used provided that the openings are larger in size than that which will support a continuous film of the liquid.

By way of illustration, in one satisfactory method of fabrication of the packing units, a suitable foraminous or screen-like material is chosen and pressed between dies to impart a parallel series of permanent sinuous or wave-like impressions to the sheets. A number of sheets, to say 3 to 12, are superimposed and then cut to shape as, for example, by means of a rotary file or high speed cut-off grinder, to form a single packing unit. The number of such units required is fixed by the height to which it is desired to fill a tower, the amplitude or perpendicular height of the waves impressed in the packing and the thickness of the individual packing units.

A particularly satisfactory material for the individual meshed structures is expanded metal sheet or lath having integral ribbon-like members and which may be fabricated from a metallic sheet by slitting a sheet of metal and operating on the slit sheet to bend or deflect the strands to produce an open diamond mesh, the bent strands extending diagonally on the sheet in opposite directions and being connected by bands extending transversely of the sheet. This structure is obtained by slitting and stretching the sheet to provide the interlocking strands.

Between about 3 and 15 layers of expanded metal lath can be arranged in mats and held together by suitable fastening devices such as bolts, wire lacing and the like. The mats may be constructed of any suitable metal including steel, nickel, copper, aluminum or other metal or alloy particularly adapted for the contemplated contacting operation. Likewise, the meshed structure can be coated or painted if desired for protection against corrosion or to alter the wetting characteristics of the individual strands.

For convenience in handling and installing packing in large diameter commercial fractionating towers, such as towers having diameters of from 3 to 8 feet, the packing unit or mat may be rolled upon itself so that it can be inserted through convenient manholes in the wall of the tower and assembled within the tower. Such rolled sections may be bound around by a removable wire, chain or the like or the edges of the mat may be spot-welded to hold the unit in the rolled shape.

An essential feature of the invention is the arrangement of the contacting mats as a series of undulating elements horizontally across the flow area of the tower. The most convenient and preferred arrangement is that wherein the wave crests of one undulating mat is disposed immediately below the lowermost portions of the next succeeding mat. The undulating pattern of the packing mats can be conveniently obtained by corrugating, pressuring or folding the individual meshed structures to produce oppositely and alternatively pitched surfaces. The individual shaped structures can then be assembled to produce a mat of the desired thickness or capacity.

The packing units or mats are installed within the tower horizontally with the ridges of one unit parallel to and in capillary contact with the lower surface of the troughs of the unit above to create a plurality of cells. To align ridges and troughs and to prevent collapse of the cells between adjacent units, the skeleton support

members or elongated cages are provided. These elongated skeleton cages do not obstruct the flow of gases and liquids through the tower but are more resistant to deformation than are the mats which form the cells. Ordinarily these cages will be quadrilateral skeletons, the sides of which form an angle of between about 25 and 75 degrees with the horizontal.

To maintain the corresponding ridges and troughs of adjacent mats and the elongated skeleton cages in close contact, tie rods are employed which traverse all the superposed mats and compress them into the desired arrangement as defined by the elongated skeleton cages. In this connection, the undulating mats may be roughly formed and the skeleton cages will align the ridges and troughs in the precise size and shape desired for the intervening cells.

The invention will be more readily understood from the following description and the accompanying drawings which illustrate preferred embodiments thereof and wherein:

Figure 1 is an elevation, partly in section, showing a column with a plurality of packing units with skeleton cages in the cells;

Figure 2 is a top plan view showing details of the apparatus assembly;

Figure 3 is a bottom plan view of the apparatus shown in Figure 1;

Figure 4 is a view in perspective showing the details of one form of the spacer element;

Figure 5 shows another form of elongated skeleton cage which is fabricated from a foraminous sheet;

Figure 6 illustrates the details of construction of the cartridge hold-down assembly;

Figure 7 illustrates one method of rolling the individual mats for introduction through a manhole;

Figure 8 is a view in perspective showing a method of installing cartridges of packing;

Figure 9 illustrates a ring seal used with cartridges of packing;

Figure 10 is an elevation in section showing a method for the support and seal of packing cartridges;

Figure 11 is an elevation in section showing a method for installing packing in small towers.

Each foraminous sheet is roughly shaped to the undulating pattern having oppositely and alternately pitched surfaces and a plurality of the roughly shaped sheets of foraminous material is nested and formed into a single unit or mat 10 by compression, for example under a drop-forge hammer. The unit is then cut to the desired size and shape to fit the tower. In order to minimize short circuiting of the units 10, a packing may be employed between the unit and the tower wall. Adjacent the tower shell, a packing comprising asbestos fiber, glass rope, or the like, and a cylindrical screen or expanded metal sheet can be provided to retain the packing.

In the installation of packing within a tower, or in prefabricating a cartridge of packing the method of assembling the packing is essentially the same. The mats 10 are superposed with the ridges 13 of one and the valleys 14 of the other being aligned to provide the cells 15 of substantially quadrilateral cross-section. Within the cells 15 is placed an elongated skeleton cage 16 and various embodiments of this cage are illustrated in the drawings. These cages define a generally quadrilateral skeleton and support the superposed mats while permitting the ridges 13 and the valleys 14 to remain in contact.

Thus, the cages 16 align the adjacent mats 10 and prevent distortion or collapse of the cartridge due to its elongated shape and substantial resistance to deformation by the weight of the superposed mats or by the pressure applied by the tie bolt assembly.

The skeleton cages may comprise a rigid wire framework as shown in Figure 4. In this embodiment, the end frame members are in the form of open quadrilateral loops 17 and 17a which correspond to the cross-sectional shape and size of the cells 15 between adjacent superposed mats 10. The loops 17 and 17a are rigidly spaced from each other by communicating elements 18 and 18a, thereby producing the rigid skeleton which is adapted to retain the cells in their original configuration without obstructing the flow of gases or vapors through the packing unit.

In addition to the preferred embodiment of the elongated skeleton cage shown in Figure 4, it is contemplated that skeleton cages 16 may be fabricated from folded sheets of heavy foraminous material capable of resisting deformation. In this embodiment, the sides 19 and 19a contact the upper wall of the cell 15 and sides 20 and 20a of the cage shown in Figure 5 contact the lower wall or floor of the cell 15. Thus, the four sides of the folded cage shown in Figure 5 positively and firmly contact the upper and lower walls of the cell 15. Accordingly, the cage being constructed of heavy foraminous or expanded metal sheet successfully resists deformation of the cell while aligning the ridges and valleys.

Still another embodiment of the skeleton cage 16 may comprise quadrilateral segments of foraminous material, such as heavy expanded metal sheet, shaped similar to the cross-section of cells 15. These rigid segments are jointed by tie members to form an elongated skeleton cage.

The folded quadrilateral cages of expanded metal sheets, such as shown in Figure 5, possess the additional feature of preventing relative movement of the superposed mats laterally and tend to anchor the adjacent mats. Furthermore, the continuous sheet in bridging the point of capillary contact between adjacent mats provides an auxiliary path for the flow of the liquid.

Figures 1, 2, and 3 show an assembled packing cartridge. In this cartridge, tie bolts 21 are provided extending between the bottom packing support grid 22 and the topmost mat in the cartridge. The supporting grid 22 comprises a parallel series of bars or tubes 23 which are transverse to the ridges 13 and the valleys 14 of the mats 10. The lower ends of the tie bolts 21 are fixed to the supporting grid 22 so that a force applied by tie bolts 21 tends to move the packing toward the grid 22. The upper ends of the tie bolts 21 are threaded to engage the nut 24 and sleeve 25 which coacts with the grid 22 to urge the adjacent mats into positive contact. This resilient contact can be made more positive, if necessary, by drawing down on the sleeves 25 after the assembled cartridge is in place. A lateral tie member 26 extends between the outer tie bolts 21 and central tie bolt 23 as shown in Figures 1 and 2 of the drawings. This member 26 is illustrated as comprising a wire loop which is shortened by twisting.

In addition to pre-fabricating the cartridge outside of the tower, the invention contemplates the fabrication of the packing assembly within the shell or tower. Thus, the individual packing unit or mat 10 may be rolled on itself about an

axis substantially parallel to the ridges and valleys and bound by a removable wire, cord or strap 27 as shown in Figure 7. These bound rolls are then passed through a manhole and unrolled within the tower. The individual mats are then threaded over the tie bolts 21 after placing the desired number of skeleton cages 16 within the valleys of the exposed mat. In connection with this mode of assembly, the skeleton cages 16 perform the added function of supporting the workmen's weight. In those instances where there is no justification for installing packing to the full diameter of a given tower, the packing cartridge may be built up within the tower in the manner illustrated in Figure 8. Sheet metal may be employed to build up the walls of the cartridge, restrained by rings 29 or circular bands. Normally, the pressure drop across lap joints 28 is so small that the amount of leakage encountered does not justify welding for purposes of seal at the lap joints. Figure 9 illustrates a manner of effecting a seal between the cartridge and tower wall by inserting an annular ring 30 and employing circumferential welds for purposes of seal. Bolted gasket seals may be used in place of welds.

In small diameter towers the cartridge form of installation shown in Figure 10 may be employed. The packing is first installed and supported in a cartridge shell and this in turn is supported and sealed within the tower by a ring 31 inserted between flanges 32 and 32a.

Another means of utilizing packing in small towers is shown in Figure 11. This method utilizes short enough tower sections for convenience in installing packing and then assembling these sections after the packing has been installed. Each section has its own supporting grid 33 and is joined to the next section by a circumferential weld 34.

The packing illustrated in the drawings is in the form of a modified sine curve, but other shapes are contemplated. Mats having simple V-shaped valleys and ridges may be used and by means of the skeleton cage supports a proper alignment and contact between the ridges and troughs of adjacent mats can be obtained.

Although we have described our invention with particular reference to certain embodiments thereof, this is for the purpose of illustration only and the invention is not limited thereto. Accordingly, it is contemplated that modifications coming within the scope of our invention can be made by those skilled in the art without departing from the spirit thereof.

What we claim is:

1. A contacting apparatus comprising a shell and a pre-fabricated cartridge including a bottom support grid, a plurality of superimposed mats constructed of a plurality of layers of wire fabric in capillary contact and having alternate ridges and valleys on their plane surfaces, the ridges of one mat coinciding with and contacting the valleys of the mat next above to provide a plurality of cells of generally quadrangular cross section disposed transverse to the vertical axis of the cartridge, elongated quadrangular skeleton cages in at least some of said cells adapted to maintain the adjacent mats in aligned relation while permitting capillary contact of the coacting ridges and valleys, tie rods extending longitudinally through the cartridge upwardly from said support grid and terminating above the topmost mat in said cartridge, and means for drawing coacting ridges and valleys of said mats

into capillary contact between said topmost mat and said grid support means.

2. In an apparatus for contacting wherein a plurality of superimposed porous mats consisting of nested contiguous foraminous sheets with alternately and oppositely pitched plane surfaces defining a plurality of parallel quadrilateral elongated cells, the improvement which comprises longitudinally adjustable tie rods extending through said mats and adapted to maintain adjacent mats in capillary contact, said mats tending to spread in a direction transverse to said cells when placed under compression by said tie rods, and a plurality of elongated quadrilateral skeleton cages removably disposed within said cells between adjacent mats to maintain the mats in the desired spaced relation and to cooperate with other skeleton cages in adjacent cells to maintain the mats in non-spreading alignment.

3. The apparatus of claim 2 including at least two tie rods in alignment along a diameter transverse to the ridges and valleys of the mats, and a lateral tie means extending between the upper ends of said tie rods above said mats whereby groups of such mats and skeleton cages can be drawn laterally between the tie rods.

4. A contacting apparatus comprising a shell and a prefabricated cartridge including a bottom support grid, a plurality of superimposed mats constructed of a plurality of layers of foraminous sheets in capillary contact with each other and having alternately and oppositely pitched plane surfaces producing a series of parallel ridges and valleys, each said mat having compliance about the axis of said ridges and valleys, the ridges of a lower mat coinciding with and contacting the valleys of the mat next above to provide a plurality of cells of generally quadrangular cross section disposed transversely to the vertical axis of the cartridge, elongated quadrangular cages in at least some of said cells, said cages having open ends and four walls of foraminous sheet material, the walls of said cages being adapted to contact corresponding oppositely and alternately pitched surfaces of adjacent mats to maintain the adjacent mats in aligned relation for capillary contact of the coacting ridges and valleys, tie rods extending longitudinally through the cartridge upwardly from said bottom support grid and terminating in the topmost mat in said cartridge, and means carried by said tie rods above said ridges for compressing said mats toward said bottom support grid and into contact with said cages.

5. The contacting apparatus of claim 4 which includes a temporary lateral draw means extending between the ends of at least two tie rods for temporarily reducing the dimension of the cartridge transverse of the valleys and ridges whereby the cartridge can be lowered into a chamber and a tight wall fit obtained by releasing the temporary draw means and permitting the cartridge to expand laterally in place.

6. A packing for a vapor and liquid contacting apparatus adapted to be arranged within a vertical cylindrical shell comprising in combination

a multiplicity of prefabricated mats composed of a plurality of foraminous sheets and having alternately and oppositely pitched plane surfaces which produce a parallel series of alternate ridges and valleys, a first mat across the entire flow area of the shell, a plurality of elongated quadrangular open-ended cages within each of the valleys of the first mat, a second mat over the first mat, arranged with the ridges of the lower first mat parallel to the valleys of the upper second mat and in capillary contact over said cages, and additional alternate groups of cages and of superposed mats above said first and second mats to provide the packing of the desired depth.

5 7. An apparatus adapted to be installed as a prefabricated contacting unit within a cylindrical chamber comprising in combination a base grid, a series of superposed mats on said grid and having alternately and oppositely pitched plane surfaces, the superposed mats producing a series of parallel cells deformable only in a direction transverse to the axis of the parallel cells, a plurality of such superposed mats threaded over at 10 least two tie rods arranged along a diameter of said chamber transverse to the axis of said cells, a plurality of quadrangular skeleton cages removably disposed within said cells, means for temporarily drawing the upper ends of said tie rods 15 toward one another so as to deform said cells and progressively reduce the diameter of the series of superposed mats, and means carried by said tie rods for applying compression to said cartridge by drawing down on said superposed mats 20 whereby said cartridge unit is maintained in wall-sealing contact with the wall of said chamber.

25 8. The apparatus of claim 2 wherein said cages comprise a folded foraminous sheet.

30 9. The apparatus of claim 2 wherein said cages comprise open quadrilateral loops rigidly spaced from each other by rod-like elements.

35 10. The apparatus of claim 6 wherein the packing is encased by metal walls separable from the cylindrical shell.

40 11. The apparatus of claim 6 wherein each of said cages comprises folded foraminous sheet.

45 12. The apparatus of claim 6 wherein each of said cages comprises a pair of spaced open quadrilateral loops held in a rigid array by rodlike elements.
